United States Patent Office.

WILLIAM C. WHIPPLE, OF NEW HAVEN, CONNECTICUT.

Letters Patent No. 92,682, dated July 13, 1869.

IMPROVED DRILLING-MACHINE.

The Schedule referred to in these Letters Patent and making part of the same.

To all whom it may concern:

Be it known that I, WILLIAM C. WHIPPLE, of New Haven, in the county of New Haven, and State of Connecticut, have invented a new Improvement in Drilling-Machine; and I do hereby declare the following, when taken in connection with the accompanying drawings, and the letters of reference marked thereon, to be a full, clear, and exact description of the same, and which said drawings constitute part of this specification, and represent, in—

Figure 1, a top view;
Figure 2, a side view;
Figure 3, an end view;
Figure 4, a sectional view on line x x ; and in
Figure 5, a detached view, for the illustration of the invention.

This invention relates to an improvement in drilling-machines; the object being to make the feed automatic, and, at the same time, to arrest the feed when the drill has advanced the required distance.

To enable others skilled in the art to construct and use my improvement, I will proceed to describe the same, as illustrated in the accompanying drawings.

A is the base or bed-plate, supporting, in bearings B, a mandrel, C, which is caused to revolve by the application of power through a band on the pulley D, which is fixed to the mandrel.

The end, d , of the mandrel is fitted to receive the drill, and the mandrel constructed so as to pass longitudinally through the bearings.

E is a pulley, loose upon the mandrel, but of a diameter slightly larger than the pulley D, and has fixed to it an open nut, a , (see fig. 4,) the nut being upon the end of the two spring-arms e . (See figs. 1 and 2.)

A portion of the mandrel, forward of the pulley E, is threaded, as seen in fig. 1, so that when the nut is closed, as in fig. 4, the thread on the mandrel will work in the thread of the nut.

The nut is closed by clamping-levers F F , and when clamped, is held by a latch, H , as seen in figs. 3 and 4, and by freeing the latch, the jaws and nut open, as seen in fig. 5.

The nut being closed upon the thread, if the two pulleys were caused to revolve at the same velocity,

there would be no advance or action of the thread on the mandrel whatever, the nut revolving with the mandrel as if a part of it; but if the pulley D be driven, and the pulley E stationary, then the mandrel would advance, in accordance with the cut of the thread on the mandrel, but the pulley E, revolving slower than the pulley D, reduces the advance of the spindle, by the action of the thread, in proportion as the revolution of the pulley E is slower than the pulley D; and, further, if the pulley E revolved more rapidly than the pulley D, then the mandrel would be retracted.

The great advantage of this construction lies in this, that if in boring and feeding by the differential pulleys, at any time, the pressure should become so great as to arrest the movement of the drill, the pulley E would continue to revolve, and consequently draw back or ease up on the mandrel until the drill would again advance; hence, the nut combined with the pulley E, of a less velocity than the pulley D, makes the feed self-adjustable and automatic, conforming the feed to the nature of the material being bored.

When the drill has entered or bored the required distance, it is desirable to arrest its further advance; I therefore arrange, in connection with the mandrel C, a sliding rod, L, which has upon it an adjustable trip, P, which, being set upon the rod, will strike the latch H, when drawn sufficiently far, and disconnect the jaws F F, so as to free the nut from the thread of the mandrel, then a spring or rod, L, will throw back the mandrel.

Having fully described my invention,

What I claim as new and useful, and desire to secure by Letters Patent, is—

1. In combination with the threaded mandrel C and its fixed pulley D, the open nut a , and its pulley E, of a larger diameter than the pulley D, so as to operate substantially as set forth.

2. In combination with the above, the sliding rod L with its trip P, so as to operate the latch H, substantially as set forth.

WM. C. WHIPPLE.
